GIRDLE

Marguerite R. Williams, New York, N. Y., assignor to Lily of France Corset Company, Inc., New York, N. Y., a corporation of New York

Application January 17, 1945, Serial No. 573,159.

2 Claims. (Cl. 2-43)

1

This invention relates to girdles. Among the objects of the invention is to provide a girdle in which the usual control effected upon the figure of a wearer is supplemented by improved control of the abdomen without impairment of comfort.

Another object of the invention is to provide a girdle having a panel arranged to mold and hold firm the abdomen of a wearer in conjunction with elastic material and side sections of horizontally inextensible material attached or otherwise tied to the panel only in regions of its greatest width, whereby the greatest horizontal pull on the panel is exerted over an area of the abdomen where forceful control is desired and in a band where the greatest stability of the front of the garment can be obtained. The action provided, in addition to effecting forceful restraint over the abdomen at the location of greatest need, causes a wearer to assume good posture without discomfort. These and other features of the invention will be best understood and appreciated from the following description with reference to the accompanying drawing showing the best mode in which I have contemplated applying the principle of my invention.

In the drawings:

Fig. 1 is a front view of a girdle embodying the principle of my invention;

Fig. 2 is a side view of the girdle as seen from the right side of Fig. 1;

Fig. 3 is a rear view of the girdle shown in Fig. 1;

Fig. 4 is an enlarged sectional view of a detail on line 4-4 of Fig. 1.

The girdle of the present invention is a body-encircling garment extending from an upper waistline edge to a bottom edge below the hips. The main portion of the front of the garment is a panel 10 consisting of substantially inelastic material. Its upper and lower edges 11 and 12 are intersected at each side of the front panel by sloping side edges which meet intermediate the longitudinal dimension of the front panel at points which define the greatest horizontal dimension of the panel.

The left side edge of the front panel, as seen in Fig. 1, is defined by intersecting edges 13 and 14 which form an obtuse angle at 15 and respectively slope inwardly of the panel, edge 13 meet-

2

ing with upper edge 11 in an obtuse angle and edge 14 meeting with lower edge 12 in an obtuse angle. The right side edges 16 and 17 meet at point 18 and each has a slope opposite to edges 13 and 14, respectively, whereby sloping edges 13 and 16 converge upwardly to upper edge 11 and sloping edges 14 and 17 converge downwardly to lower edge 12 from an imaginary horizontal line 19 passing through points 15 and 18. The front panel consequently is of an hexagonal form. While the degree of slope and the configuration of side edges 13, 14, 16 and 17 may vary, it is the aim of the invention to locate the greatest width of the front panel with respect to the body of a wearer so that it may be held relatively fixed between points 15 and 18, whereby the front panel 10 is horizontally tensioned against the abdomen, as will appear hereinafter from the description of the remaining portions of the garment.

20 The garment is so designed that the imaginary horizontal line 19 (generally described as passing through the regions of intersection of sloping sides 13 and 14, and of intersection of sloping sides 16 and 17) will be located in line with the hip bones of the wearer.

In order that the garment shall have sufficient elasticity above and below the imaginary horizontal line 19 to respond to movements of a person wearing the garment, horizontally extensible pieces of material, such as elastic fabric, are attached to the longitudinal edges of the central panel. These pieces of extensible material constitute and fill tapered areas at 20, 21, 22 and 23. The upper edges of elastic materials 20 and 22 are in continuation of the upper edge 11 of the front panel and their front longitudinal edges are sewed to the sloping edges 13 and 16, respectively, of the front panel. The lower edges of elastic materials 21 and 23 are in continuation 35 of the lower edge 12 of the front panel, and the front longitudinal edges of these elastic materials are sewed to the sloping edges 14 and 17, respectively, of the front panel. While the material covering the areas 20 and 21 may originally be 40 separate from one another, it is preferred that the upper area 20 and the lower area 21 be of one piece having the general shape of the combined areas 20 and 21. This is also true with 45 respect to the elastic material in upper and lower

areas 22 and 23 at the other side of the front panel.

The portions of the garment which bear against the sides of the person wearing the same are formed alike and of substantially inelastic material. They extend from the upper to the lower edge of the garment. These pieces constitute side sections 24 and 25. The front edge 26 and rear edge 27 of each of these side sections are suitably curved to conform to the figure of the wearer, but in the main extend longitudinally of the garment.

The edges of the front panel preferably lie adjacent the front edges 26 and 26' of the side sections 24 and 25, respectively, at regions 15 and 18. Each of the side sections is attached to the front panel only opposite regions 15 and 18, respectively. This has the effect of properly locating the garment on the wearer and of extending the effective length of non-stretchable material across the front of the garment to the rear edges of the side sections and, therefore, around the body of the wearer beyond the lateral extremities of the front panel. The front panel is thereby firmly held against the abdomen.

So as to assure an inextensible connection between the front panel and side sections 24 and 25, it is desirable that they be tied together opposite regions 15 and 18 of the front panel. One manner of accomplishing this is shown in Figs. 1 and 4 as constituting a tape 28. The tape is sewn to the side section 24 and to the front panel 10 and extends across their edges on the inner side of the garment. The material designated 30 in Fig. 4 is the connecting portion of the piece of elastic material filling areas 20 and 21. Vertically extending tapes 31 and 32 overlie tape 28 and extend over the elastic material and along the longitudinal front edge of side section 24 and along the sloping edges 13 and 14 of the front panel.

Inasmuch as an opening is required for adjusting the garment on the person of a wearer, the garment is provided with a longitudinal opening at 33, which is closable at will. This opening may be conveniently placed between the elastic material filling areas 22 and 23 and side section 25. For closing the opening a slidible clasp and track 35, or hooks and eyes, may be used and such mechanical means will serve to secure the front edge 26' of side section 25 to the front panel opposite region 18, as well as close the entire length of the opening. If the opening and means for closing the same is placed elsewhere a tying tape similar to tape 28 could be employed to connect the front and side section opposite region 18.

The rear portion of the garment may be variously formed with non-extensible material and horizontally extensible material sewed together and assembled as a rear section. In the drawings I have shown a rear panel 36 of inextensible material extending longitudinally of the garment from its upper to its lower edge. One side edge 37 of this rear panel is secured to a longitudinally-extending strip 38 of horizontally extensible material which likewise extends from the upper to the lower edge of the garment and is attached to side section 25 along edge 39. A similar strip of horizontally extensible material 40 is attached to the side edge 41 of the rear panel 36 and to the rear edge 27 of side section 24.

It will be appreciated that the tapering areas of elastic material 20 and 22 at the waist of the garment and tapering areas of elastic material 21 and 23 at the lower part of the garment will provide flexibility at the front of the garment in

increasing amount proportional to the remoteness of any point thereon from the imaginary horizontal line 19 and that the greatest restraint upon the person of the wearer will be exerted along the imaginary line 19. This will tend to press and support the abdomen at the location of its greatest need. The combination of conditions that produce the best average result is attained when the garment is so formed that the extremities of the maximum width of the front panel reach the crests of the hip bones at either side of the figure.

It is preferable that the upper edge 11 of the front panel be provided with an elastic gore 43 at its center so as to relieve the tightness of the girdle along its upper edge when the wearer assumes a sitting position. The usual hose supporters 44, 45, 46, 47, 48 and 49 may be attached to the lower portion of the garment, as desired.

What is claimed is:

1. A girdle comprising a tubular garment for encircling the body of a wearer from an upper waistline edge to below the hips, said tubular garment including a central front panel of horizontally inextensible material with its greatest dimension extending longitudinally from the upper edge of the garment to the lower edge of the garment and having opposite side edges converging upwardly to the upper edge of the panel and downwardly to the lower edge of the panel and thereby locating the greatest horizontal dimension of the front panel in line with the hip bones of a wearer, longitudinally extending side sections of horizontally inextensible material, said side sections being attached to said opposite side edges of said front panel, one at each side, only at the extremities of said greatest horizontal dimension of said front panel, horizontally extensible pieces of material attached to said front panel along its converging opposite side edges and to said side sections along their longitudinally extending front edges, there being one of said pieces of material extending in one-piece from the upper to the lower edge of the garment at each side of said front panel and thereby providing upper and lower horizontally extensible tapering areas adjacent the converging side edges of said front panel with progressively increasing extensibility laterally of the front of the garment upwardly and downwardly from the greatest horizontal dimension of the front panel, a rear section having its side edges attached to the rear edges of said side sections to complete the tubular garment, and an opening part way along one seam of said garment and means for closing said opening.

2. A girdle comprising a tubular garment for encircling the body of a wearer, said tubular garment having such length as to extend from an upper waistline edge to below the hips and comprising a front panel of substantially inelastic material having an upper edge in the upper edge of the garment, a lower edge in the lower edge of the garment and opposite side edges, each of said opposite side edges being broken into two lines meeting in an obtuse angle whose apex lies substantially over the hip bone of a wearer, side sections of substantially inelastic material extending from the upper edge of the garment to the lower edge of the garment and connected to said front panel only at the said apices formed by said broken lines of each of the opposite side edges of said front panel, relatively inextensible means connecting said side sections to said apices of said front panel whereby the horizontal inextensibil-

ity of said front panel is prolonged to the rear edges of said side panels through said apices of said front panel, horizontally extensible pieces of material attached to said front panel along its said opposite side edges and to said side sections along their longitudinally extending front edges and providing upper and lower tapering areas which converge on the apices formed by said broken lines of the opposite side edges of said front panel, a rear section comprising a substantially rectangular panel of substantially inelastic material extending from the waist to the lower edge of the garment and horizontally extensible pieces of material attached to said rear panel along its longitudinally extending side edges and to the rear edges of said side panels, and an

opening part way along a seam of said garment and means for closing said opening.
